United States Patent Office.

HENRY E. SHAFFER, OF ROCHESTER, NEW YORK.

Design No. 3,806, dated December 21, 1869.

DESIGN FOR A FRUIT-JAR COVER.

The Schedule referred to in these Letters Patent and making part of the same.

To all whom it may concern:

Be it known that I, HENRY E. SHAFFER, of the city of Rochester, county of Monroe, and State of New York, have invented and produced a new and original Design for Fruit-Jar Covers, of which the following is a full and exact description, referring to the accompanying drawing, in which—

Figure 1 is a plan, and

Figure 2, a vertical section.

This design consists of a glass cover, of the form hereafter described.

In the drawings—

A is the cover.

It has a depressed centre, *a*, which rests in the neck of the jar, and a groove, *b*, which receives the neck.

Outside, it has a flange, *c*, with two sharp edges, *d*, which strike down upon the packing.

Above this, the cover is formed with a graceful bead or swell, *f*, at the periphery, leaving a plain ring, *g*, within, for the bearing of the clamp; and still within this, a sunken space, *h*, which follows the depressed bottom *a*.

This design presents a graceful exterior, while at the same time, it subserves a useful purpose in being adapted to the form of the jar.

What I claim, and desire to secure by Letters Patent, is—

The design for fruit-jar cover, as shown.

In witness whereof, I have hereunto signed my name, in the presence of two subscribing witnesses.

H. E. SHAFFER.

Witnesses:

R. F. OSGOOD,

GEO. W. MIATT.
